UNITED STATES PATENT OFFICE.

WILLIAM ISAIAH McCUSAULAND, OF FLAT RIVER, MISSOURI.

PHOTO-SMOKE ARRESTER.

No. 920,370.

Specification of Letters Patent.

Patented May 4, 1909.

Application filed October 2, 1907. Serial No. 395,617.

To all whom it may concern:

Be it known that I, WILLIAM ISAIAH McCUSAULAND, citizen of the United States, residing at Flat River, in the county of St. Francois and State of Missouri, have invented certain new and useful Improvements in Photo-Smoke Arresters, of which the following is a specification.

The present invention is in the nature of a novel device for arresting and confining smoke and gases given off by flash light powders such as are employed for photographic and theatrical purposes.

The object of the invention is to design a smoke arrester of this character which is of simple and inexpensive construction and operates in an effective manner to confine the smoke and prevent it from escaping into the room where it is extremely objectionable owing to the fact that it has a corrosive action upon certain fixtures and fills the air with poisonous gases.

To this end the invention resides principally in the provision of a collapsible hood and a novel means for mounting the hood over the burning powder, the said hood operating when distended to suck up the smoke and fumes produced by the combustion of the powder.

For a full description of the invention and the merits thereof and also to acquire a knowledge of the details of construction and the means for effecting the result, reference is to be had to the following description and accompanying drawings, in which:

Figure 1 is a vertical sectional view showing the device mounted upon the standard and the hood as pressed downwardly within the box. Fig. 2 is an end view of the same, the lid being shown in an elevated position. Fig. 3 is a perspective view of the device when folded. Fig. 4 is a vertical sectional view through the device, the hood being shown as moved upwardly into an operative position and as partially distended. Fig. 5 is an end view of the device when in the position shown in Fig. 4, the lid being closed. Fig. 6 is a vertical sectional view with the hood distended. Fig. 7 is a horizontal sectional view on the line 7—7 of Fig. 6.

Corresponding and like parts are referred to in the following description and indicated in all the views of the drawings by the same reference characters.

Referring to the drawings the numeral 1

designates the box which may be formed of any light and fire-proof material such as aluminum, one of the sides of the box being open and provided with an upwardly swinging cover 2. Passing centrally through the box 1 is an upright standard or rod 3 which may be supported by any suitable means such as the usual tripods. The upper portion of the box 1 is designed to be closed when the apparatus is collapsed as shown in Fig. 3 by means of a cover 4 and a frame 5 is secured to the mouth of the box 1 within the upper portion thereof, the inner faces of the frame being beveled inwardly as indicated at 6. A collapsible hood is mounted upon the standard 3 immediately over the box 1, the said hood comprising an upper frame 7 which is shown as secured to the cover 4 of the box, a lower frame 8, and bellows 9 connecting the two frames.

When the apparatus is folded for transportation the lower frame 8 fits within the box 1 and the cover 4 closes the top of the said box. When the device is set up for use however the lower frame 8 is moved into engagement with the frame 5 secured to the box 1 and is held in engagement therewith by means of the toggle levers 10 secured respectively to the frame 8 and the bottom of the box 1. It will be observed that in the present instance the outer faces of the lower frame 8 are beveled outwardly corresponding to the beveled faces 6 of the frame 5 and engage with the same to produce a practically air tight joint. The bellows 9 may be of any conventional construction and in the present instance is shown as formed of fire-proof cloth having the spaced annular rings 11 secured thereto.

Surrounding the standard 3 and interposed between the upper frame 7 and lower frame 8 of the collapsible hood is a coil spring 12 which normally operates to force the said frames apart and hold the bellows in a distended position. For the purpose of holding the upper frame 7 down against the action of the spring 12 in which position the hood is collapsed, a catch 13 is fastened to the top 4 and engages a pivoted catch 13^a supported from the pan 18.

Extending downwardly from the catch 13^a is an operating cord 14 which passes through a guide member 15 and then extends outwardly away from the standard where it engages a lever 16, after which it hangs downwardly and terminates in a finger-piece 17.

The flash light powder is designed to be placed upon a pan 18 within the box 1 and to be discharged by a cap or ignitable pellet of the usual character. For the purpose of igniting such a pellet, a spring actuated hammer 19 is provided, the said hammer being tripped through the medium of the lever 16. This hammer 19 may be of any approved construction, and as shown on the drawings, comprises a plate which extends over the nose of the lever 16, and a stem which is pendent from the plate and is normally pulled downwardly into contact with the anvil by means of a coil spring surrounding the same, the cap or ignitable pellet being designed to be placed between the stem and the anvil. It will thus be apparent that when a downward pull is exerted upon the finger-piece 17 the lever 16 is moved to raise the hammer 19 against the action of the spring, after which it is released and caused to strike against the cap to ignite the same. A further movement of the operating cord serves to release the catch 13 whereupon the spring 12 forces the frame 7 upwardly and the bellows 9 is distended. The upwardly swinging cover or lid 2 is normally held in a raised position by means of a cord 20 which engages the standard 3, preferably at the upper extremity of the same.

Projecting upwardly from the top of the collapsible hood is an arm 21 which in the present instance is shown as terminating in a ring 22 slidable upon the standard. When the collapsible hood is distended by releasing the catch 13 as previously described the arm 21 moves upwardly along the standard and the ring 22 at the extremity thereof disengages the cord 20, whereupon the lid 2 falls downward by the action of gravity and closes the open side of the box. It will be observed that the said swinging lid is provided with the flanges 23 and these flanges are preferably lined with felt or analogous material so as to produce a smoke tight closure. It will thus be apparent that by a single pull upon the finger-piece 17 at the extremity of the operating cord the flash light powder is ignited, the collapsible hood distended so as to suck up the smokes and gases produced by the combustion of the powder, and the lid 2 caused to swing downward and close the open side of the box, thereby effectively confining the smoke until the apparatus shall be moved into the open air or other position where it is desired to release the smoke. It might be mentioned that by suitably varying the length of the arm 21 the time allowed after the ignition of the flash light powder before the swinging lid 2 is closed can be conveniently regulated.

When the device is not in use the toggle levers 10 are moved outwardly and the lower frame 8 of the hood caused to enter the box 1. The cover 4 can then be applied to the top

of the box and secured in position by any suitable means.

Having thus described the invention, what is claimed as new is:

1. A flash light smoke arrester comprising a box formed with an open side, a movable lid for closing the open side, a collapsible hood arranged in coöperative relation to the box, means for distending the hood, and means for automatically closing the lid when the said hood is distended. 70

2. A flash light smoke arrester comprising a box formed with an open side, a movable lid for closing the open side, a collapsible hood arranged in coöperative relation to the box, a spring for distending the hood, means for holding the hood collapsed against the action of the spring, means for releasing the hood, and means for automatically closing the lid when the hood is distended. 80

3. A flash light smoke arrester comprising a standard, a box mounted upon the standard and formed with an open side, a swinging lid for closing the open side, a cord loosely engaging the standard for holding the lid in an open position, and means for automatically releasing the cord from engagement with the standard for closing the lid. 90

4. A flash light smoke arrester comprising a box formed with an opening, a frame applied to the box and surrounding the opening and having the inner edges thereof beveled, a collapsible hood provided with a frame having beveled edges engaging the correspondingly beveled edges of the before mentioned frame applied to the box, and means for distending the hood. 95

5. In a flash light smoke arrester, the combination of an upright standard, a box supported upon the standard, upper and lower frames slidable upon the standard above the box, the lower frame engaging the said box, a bellows connecting the frames, and means for moving the upper frame to distend the bellows. 105

6. In a flash light smoke arrester, the combination of an upright standard, a box mounted upon the standard and formed with an open side and an open top, a swinging lid for closing the open side, a cord connected to the lid and detachably engaging the standard to hold the lid in an open position, a collapsible hood mounted upon the standard over the box and engaging the open top thereof, means for distending the hood, 115 and means carried by the hood to disengage the before mentioned cord from the standard and close the lid. 120

7. In a flash light smoke arrester, the combination of a standard, a box mounted upon the standard and having an open top, a frame engaging the top of the box, a second frame slidable upon the standard, bellows connecting the frames, a spring for forcing the frames apart, catches coöperating with 125

each other to hold the frames together, and means for releasing the catches to distend the bellows.

8. A flash light smoke arrester comprising a box, a frame applied to the box, a collapsible hood formed with a frame designed to engage the before mentioned frame, means for distending the hood, and toggle levers for holding the two frames normally in engagement with each other.

9. A flash light smoke arrester comprising a box, a collapsible hood formed with a frame adapted to detachably engage the box, toggle levers for holding the frame in engage-

ment with the box, and means for distending the hood.

10. A flash light smoke arrester comprising a box, a collapsible hood arranged in coöperative relation to the box, a spring for distending the hood, catches for holding the hood in a collapsed condition, and means for automatically releasing the catches.

In testimony whereof I affix my signature in presence of two witnesses.
